UNITED STATES PATENT OFFICE.

THOMAS J. CAHILL, OF LOPEZ, PENNSYLVANIA.

RAIL TIE AND BRACE.

SPECIFICATION forming part of Letters Patent No. 729,539, dated June 2, 1903.

Application filed March 9, 1903. Serial No. 146,946. (No model.)

To all whom it may concern:

Be it known that I, THOMAS J. CAHILL, a citizen of the United States, and a resident of Lopez, in the county of Sullivan, State of Pennsylvania, have invented certain new and useful Improvements in Rail Ties and Braces, of which the following is a specification.

This invention relates to rail-fastenings; and the primary object of the invention is to provide a simple article of this character adapted to effectually prevent spreading of the rails.

The improved device, which can be inexpensively and readily made, includes in its construction a tie and rail clamping or locking blocks, and these parts may be made of any suitable material. For example, they may be castings.

The tie has channels or depressions near its opposite ends in the upper face thereof, the end walls of which are undercut, the inner undercut walls being of a shape to agree with and to snugly receive the inner sides of the rail flanges or bases, the clamping-blocks in question being located between the outer flanges and the outer undercut walls of said depressions and acting to positively maintain the rails in parallelism. These clamping or stop blocks and the manner in which they operate with the tie form the prominent feature of my invention, and the peculiar construction thereof will be hereinafter fully set forth.

The invention is clearly represented in the accompanying drawings, forming a part of this specification, in which—

Figure 1 is an elevation of the improved fastening, the rails being shown in cross-section. Fig. 2 is a plan view of one end of the same. Fig. 3 is a detail perspective view of a clamping-block.

Like characters refer to like parts in the several figures.

The improved rail-fastening includes a tie, as 2, which is preferably made of metal and of the same length, or approximately so, as those ordinarily in use. Said tie has near its opposite ends the transverse channels or depressions 3, the end walls of which, it will be seen, are undercut. The bottoms of these channels or depressions are flat to provide a staple bearing for the rails supported thereon.

The inner undercut walls are adapted to snugly receive the inner sides of the bases of the rails.

Between the rails and the outer undercut walls of the channels or depressions 3 are disposed the clamping-blocks 4, one for each rail, the channels being wider than the bases of the rails in order to accommodate said blocks. The under sides of these blocks fit flatwise upon the bottom of the channels or depressions, whereby they are firmly supported. The inner lower sides of the blocks are recessed in order to receive the outer sides of the rails, such recesses agreeing substantially in shape with the undercut inner walls of the depressions, from which it will be understood that such walls, in connection with the overhanging portions of the blocks, maintain the rails down.

The outer undercut walls of the depressions 3 are beveled or acute angular with respect to the bottoms thereof, the lower outer sides 4^a of the blocks being upon like angles, and such angular or beveled portions of the blocks and walls being adapted to engage each other to thereby hold such blocks against tipping upward at their outer ends. The inner sides of the blocks are perpendicular to fit solidly against the outer similarly-disposed faces of the webs of the rails. I do not rely wholly upon the engagement between the beveled faces hereinbefore mentioned to hold the blocks in place, as in practice I prefer to drive spikes 5 through the same and the ties 2 to insure such result, the outer upper sides of the blocks having cut-out portions or indentations 6 to receive the heads of the spikes. These cut-out portions or indentations are open on their outer sides to provide for the ready insertion of a spike-drawing implement.

Above the beveled faces 4^a on the blocks are the shoulders 7, extending entirely across the same and which overlie and bear upon the upper face of the tie.

The rails are first laid in the channels or depressions 3, and the inner sides of their flanges or bases are then firmly fitted against the inner undercut walls of the depressions. The blocks 4 are then introduced into the spaces between the rails and the outer undercut and beveled walls of said channels or depressions, the fit between the rails and

beveled walls and intermediate blocks being preferably a driving one, so as to securely hold the rails against outward movement when the blocks are driven into place, and this may be done from either side of the tie. The beveled faces hereinbefore mentioned are brought into contact, and at the same time the shoulders 7 ride or bear upon the upper side of the tie. These shoulders by having a firm support upon the tie prevent the same from tipping or rocking downward at their outer ends, and thereby secure the rails against upward displacement.

Not only is the device simple and effective, but its use avoids the employment of a large number of spikes for holding the rails in place.

Having thus described the invention, what I claim is—

1. In a rail-fastening, a tie having channels in its upper face near opposite ends thereof, the walls of which are undercut, and rail-clamping blocks supported on the bottoms of said channels, having their lower sides shaped

to agree with and to fit against the outer undercut walls and having shoulders extending 25 entirely across the same and bearing against the upper side of said tie.

2. In a rail-fastening, a tie having channels in its upper face the walls of which are undercut, and rail-clamping blocks supported 30 on the bottoms of the respective channels, having beveled outer ends to fit against correspondingly-inclined faces of the outer undercut walls, notches in their inner lower corners to receive the outer portions of the rail's 35 flanges, vertical inner straight faces to fit against the outer faces of the rail-webs, and shoulders above their beveled outer ends to overhang and solidly engage the tie ouside the channels.

In testimony whereof I have hereunto set my hand this 4th day of March, 1903.

THOMAS J. CAHILL.
